VALVE FOR MEDICAL APPARATUS AND THE LIKE

Glenn L. Beall, Wildwood, Ill., assignor to Abbott Laboratories, North Chicago, Ill., a corporation of Illinois

Filed Dec. 24, 1962, Ser. No. 72,939

Term of patent 14 years

(Cl. D16—2)

FIG. 1

FIG. 2

FIG. 4

FIG. 3

FIG. 5

FIG. 7

FIG. 6

FIGURE 1 is a perspective view of a valve for medical apparatus and the like showing my new design;

FIGURE 2 is a front elevational view thereof;

FIGURE 3 is a rear elevational view thereof;

FIGURE 4 is a top plan view thereof;

FIGURE 5 is a left side elevational view thereof;

FIGURE 6 is a right side elevational view thereof; and

FIGURE 7 is a bottom plan view thereof.

The dominant features of the design reside in the portions shown by solid lines.

I claim:

The ornamental design for a valve for medical apparatus and the like, substantially as shown and described.
